UNITED STATES PATENT OFFICE

THOMAS MITFORD MOORE, OF TORONTO, ONTARIO, CANADA

THREE WAY ENVELOPE

Application filed October 30, 1928. Serial No. 315,962.

My invention relates to improvements in three way envelopes, and the object of my invention is to devise an envelope which may be used three times instead of once as in the case of an ordinary envelope or three times instead of twice as in the case of an ordinary return envelope without being mutilated in any way, leaving the interior surfaces of the envelope body and sides free and clear for the

10 purposes of corresponding or other means of communication, advertising, etc. The invention consists of an envelope having a main body portion and four flaps extending from the top, bottom and sides of that portion, so 15 formed and folded that a postage stamp may be used as a seal in two of the three transmissions through the mail and only one gummed surface on the envelope is required, as opposed to two or more gummed surfaces 20 on ordinary return envelopes, all as herein-after more particularly described.

Fig. 1 is a plan view of the envelope opened out.

Fig. 2 illustrates the first step in folding 25 the envelope when it is being sent for the first time.

Figs. 3 and 4 are the second and third steps respectively.

Fig. 5 represents the first step in folding 30 the envelope when it is being returned to the sender.

Figs. 6 and 7 are the second and third steps respectively.

Fig. 8 represents the first step in folding 35 the envelope when it is being sent again to the person to whom it was addressed in the first place.

Figs. 9 and 10 are the second and third steps respectively.

40 In the drawings like characteristics of reference indicate corresponding parts in each figure.

1 is the main body portion of the envelope. 2° and 2^x the side flaps. 3 is the top flap 45 of the envelope which is not quite as high as the main body portion and has a gummed portion 4 along the longitudinal edge separated by a perforated line 7. The sender's return address is printed or otherwise placed 50 on the back of said flap. 5 is the bottom flap

of the envelope which, is not as large as the main body portion of the envelope, and is preferably cut with a curved edge extending from end to end and terminating at the ends of the portion 1 so that there will be no corners and a postage stamp 6 may be used for sealing purposes in connection therewith as shown in Fig. 4, the flap 5 having the sending address placed upon its back.

When the envelope is to be used it is opened 60 out as shown in Fig. 1. The sender being the first person to use the envelope, if it is to be unsealed, folds down the top flap 3 as shown in Fig. 2. The flaps 2^x and 2° are next folded over, then the bottom flap 5, having any sending address placed upon its back, is folded over the end flaps, exposing the address on the outside of the envelope, as in Fig. 4. It is not necessary to seal this flap 5 because being neither the same size or shape as the body 70 1 of the envelope or of the end flaps, a portion of the underlying part remains uncovered and a postage stamp placed as indicated at 6 to adhere to the bottom flap and to one or both of the underlying end flaps serves to effectively close the envelope for mailing. If the sender desires to seal the envelope he may first fold in the end flaps, then fold the top flap 75 thereover without sealing same, then fold over the bottom flap and seal with a stamp 80 placed to extend over the edge of the bottom flap.

When the person to whom the envelope is addressed receives it, he opens it by breaking the stamp. Then having read the information printed on the inside of the envelope or contained therein, he places the cheque or note on the main body portion, and then refold the envelope as indicated in Figs. 5, 6 and 7, utilizing the gummed surface 4 in sealing. The envelope is then opened by breaking the flap 3 along the line of perforation 7, avoiding tearing the main body of the top flap 3. If it be desirable to return a receipt to the party remitting, the envelope is folded as indicated in Figures 8, 9 and 10 and a postage stamp applied as shown seals the envelope, or if sealing is not necessary the flap 3 may be folded in first and covered by the end flaps 100

and the bottom flap folded thereover and secured by a stamp.

The envelope as described is extremely simple to make, requiring but one sealing surface while the method of addressing, folding and sealing allow it to take the place of three envelopes and an enclosure such as are used in customary routine, providing also by this method of folding the option of mailing 10 the missive sealed or unsealed thus allowing for considerable saving in postage as well as labor and material. It provides, in addition at all times, a perfectly flat, plain back which may be utilized as an advertising medium.

15 What I claim as my invention is:—

1. A three way envelope comprising a paper sheet having a top flap folded inwardly and having a return address space on the back thereof, a pair of end flaps folded inwardly to overlap each other and overlying the top flap, a bottom flap to receive the primary address folded to cover a portion only of the overlapping portions of said end flaps, and a seal separably connecting said bottom and end flaps leaving the envelope unsealed.

2. A three way envelope comprising a paper sheet having a top flap folded inwardly and formed with a separable strip gummed on the inside, said flap having a return address space on the back, a pair of end flaps folded inwardly and overlapping each other at the ends, an ungummed bottom flap folded to cover a portion only of the overlapping portions of the end flaps, and a seal separably connecting said bottom and end flaps leaving the envelope unsealed.

3. A three way envelope comprising a paper sheet having a rectangular message space, a top flap adapted to fold inwardly over said message space and having a return address on its outward side, a pair of end flaps adapted to fold over and completely cover said message space on said top flap, a bottom flap of lesser area than said overlapping end flaps adapted to fold thereover leaving a portion thereof uncovered and having an address space on the outer side, and separate means 45 for sealing said bottom flap to secure the envelope sealed or unsealed.

4. A three way envelope as claimed in claim 1 in which the top flap is adapted to be folded over the infolded end and bottom flaps and sealed to the bottom flap to form a sealed envelope.

THOMAS MITFORD MOORE.
